US0D1034493S

(12) **United States Design Patent** (10) Patent No.: **US D1,034,493 S**
(45) Date of Patent: ** Jul. 9, 2024

(54) **CHAMBER WALL LINER FOR A SEMICONDUCTOR MANUFACTURING APPARATUS**

(71) Applicant: **AP SYSTEMS INC.**, Hwaseong-Si (KR)

(72) Inventors: **Chang Min Kwon**, Hwaseong-si (KR); **Chang Kyo Kim**, Hwaseong-si (KR)

(73) Assignee: **AP SYSTEMS INC.** (KR)

(**) Term: **15 Years**

(21) Appl. No.: **29/891,977**

(22) Filed: **May 11, 2023**

(30) **Foreign Application Priority Data**

Nov. 25, 2022 (KR) 30-2022-0049283

(51) **LOC (14) Cl.** **13-03**

(52) **U.S. Cl.**

Primary Examiner — Elizabeth J Oswecki

(74) Attorney, Agent, or Firm — Renaissance IP Law Group LLP

(57) **CLAIM**

The ornamental design for a chamber wall liner for a semiconductor manufacturing apparatus, as shown and described.

DESCRIPTION

FIG. 1 is a perspective view of a chamber wall liner for a semiconductor manufacturing apparatus, showing our new design;

FIG. 2 is a front view thereof;

FIG. 3 is a rear view thereof;

FIG. 4 is a left side view thereof;

(Continued)

FIG. 5 is a right side view thereof;
FIG. 6 is a top plan view thereof; and,
FIG. 7 is a bottom plan view thereof.

1 Claim, 6 Drawing Sheets
